VEHICLE FOR GOLFERS AND THE LIKE

Humbert R. Rogant, Willoughby, Ohio

Application July 17, 1953, Serial No. 26,034

Term of patent 7 years

(Cl. D90—8)

To all whom it may concern:

Be it known that I, Humbert R. Rogant, a citizen of the United States, residing at Willoughby, State of Ohio, have invented a new, original, and ornamental Design for a Vehicle for Golfers and the like, of which the following is a specification, reference being had to the accompanying drawing, forming a part hereof.

Figure 1 is a perspective side view of a vehicle for golfers and the like, showing my new design, and

The dominant features of my design reside in the portions shown in full lines.

I claim:

The ornamental design for a vehicle for golfers and the like, substantially as shown and described.

HUMBERT R. ROGANT.
